BREATHING DEVICE

Saturnino Tofé Bonilla, New York, N. Y.

Application December 21, 1942, Serial No. 469,594

2 Claims. (Cl. 128—14)

My invention relates to a new and improved breathing device, which can be used in connection with diving apparatus, swimming masks and other swimming appliances, gas masks and other life-saving devices.

One of the objects of my invention is to eliminate the use of the heavy and cumbersome and expensive inflatable swimming garments which are now used as life-saving devices.

Other objects are to produce a simple and reliable device, which can be easily manufactured and used.

Numerous additional objects of my invention will be stated in the annexed description and drawings, which illustrate preferred embodiments thereof.

Fig. 1 is an elevation of a float which embodies the improvements, and which is used to supply air to a diver.

Fig. 2 is a section on the line 2—2 of Fig. 1.

Fig. 3 is a section on the line 3—3 of Fig. 2.

Fig. 4 is a side elevation showing the invention applied to a swimming mask.

Fig. 5 is a longitudinal sectional view of the top part or breather part of the device which is shown in Fig. 4.

Fig. 6 is a sectional view of the horizontal valve structure which is shown in Fig. 4.

Fig. 7 illustrates the reversal of the parts of Fig. 6.

Fig. 8 is an elevation of the insert which is a part of the device which is shown in Fig. 6.

Fig. 9 is an elevation which shows the device for clamping the insert which is shown in Fig. 8, to the body of the valve structure which is shown in Fig. 6.

Fig. 10 is a front elevation, which is taken at the left-hand side of Fig. 9.

Fig. 11 is a sectional view on the line 11—11 of Fig. 4.

Fig. 12 is a sectional view on the line 12—12 of Fig. 4.

Fig. 13 is a section on the line 13—13 of Fig. 11.

Fig. 14 is a section on the line 14—14 of Fig. 11.

Fig. 15 illustrates a partial mask which is combined with the improved breathing device.

The embodiment of Figs. 1-3 shows an upper casing 1 and a lower casing 2. Said casings are made of metal, rigid plastic, or any other suitable material. Casing 1 is closed at its top. Casing 2 is open at its bottom. The bottom end of casing 1 is fixed in a cup 3 which has a horizontal wall 4, which has a depending frusto-conical wall 8a. For convenience, the parts are described with reference to the position shown

in Figs. 1 and 2, in which the longitudinal axis of the device is vertical.

The upper end of casing 2 is fixed to cup 6, which has a horizontal wall 7, which has a frusto-conical wall 8. Walls 4 and 7 are fixed to each other. Walls 8 and 8a are also fixed to each other. All joints are water-tight and gas-tight.

Spaced arms 9 are fixed to wall 7 and to the edge of a baffle wall 10. Wall 21, which has a frusto-conical projection 20, is fixed to casing 2.

Pipe 11 is fixed to a cylindrical projection of wall 10.

Inner casing 12 is fixed to pipe 11 at the top of said pipe, and also between the top of said pipe 11 and wall 4.

Pipe 11 has ports 14. Inner casing 12 has valve-free ports 15a, and additional ports which are associated with respective closure valves 44. Each valve 44 is fixed to a resilient rod 45, whose upper end is fixed to inner casing 12. Each valve 44 is biased to closing position by the respective resilient rod 45, which acts as a light spring.

Casing 1 has outlet ports 15, which are normally closed by valves 17. Each valve 17 is fixed to a resilient rod 18, which is fixed to casing 1 by members 19.

A float valve 22, made of cork or other suitable material, is fixed to a collar 23 which is freely slidable on pipe 11. Stop 24, which is fixed to pipe 11, limits the downward sliding movement of collar 23.

Float 25, which is made of cork or other suitable material, is fixed to collar 26, which is fixed to pipe 11.

Pipe 27 is connected to a port of pipe 11. The outer end of pipe 27 is threaded into a coupling 28, which has a head whose shape is that of a part of a sphere. Pipe 31 has a similar head 29, which fits against a part of the inner wall of the head of coupling 28. Nut 30 maintains the assembly between the parts. Sealing gaskets can be used to provide water-tight and gas-tight joints.

Flexible rubber pipe 32 is connected to pipe 31. Said pipe 32 is connected to the helmet of the diver.

Extension pipe 37 is fixed to the lower end of pipe 11. Weight 42 is fixed to the lower end of pipe 37.

Said pipe 37 has a valve seat 33, whose bore is normally closed by valve 34, which is biased to closing position by compression spring 35. Fig. 2 shows valve 34 in the open position. The stem of valve 34 passes through one of the bores 55 of a partition 35, which is fixed to pipe 37. Said

pipe 37 has an outlet port 38, which is normally closed by valve 39, which is fixed to resilient arm 40, which is fixed by members 41 to pipe 37.

In Fig. 1, the normal water level is indicated by line L. Float 25 has enough buoyance to maintain the device normally in the position shown in Fig. 1, with the float-valve 22 located normally wholly above the water-level. Ports 15 are maintained above the water-level. The weight 42 biases the device to float in the normal vertical position, like a buoy.

When the diver inhales, air can enter the casing 2 through its open bottom. The air in casing 2 below wall 21, will pass upwardly through the space between pipe 11 and the flange or projection 20. Said incoming air will flow around the edge of deflecting or baffle wall 10, together with the air in the casing 2 above wall 21, through the spaces between arms 9, through the flange or projection 8a, through ports 15a and ports 14, and downwardly through pipe 11 and through pipes 27, 31 and 32 to the helmet of the diver.

When the diver exhales, air will flow upwardly through pipe 32, through pipes 31 and 27, and upwardly through pipe 11, and through ports 14 and 15. If the float valve 22 then temporarily closes the bottom of casing 2, the increased air pressure in casing 1 will open valves 17, so that foul air can pass into the atmosphere. If the excess air pressure between pipe 17 and inner casing 12 is sufficient, valves 44 will be opened, in order to permit the excess air to enter the space between the casings 12 and 1.

If the float-valve 22 is normally spaced from the rim of casing 1, as shown in Fig. 1, a wave or sudden downward movement of the device will move the float-valve 22 upwardly to close the bottom of casing 2, in order to prevent water from entering casing 2. If water splashes into the device, said water normally runs out when the float-valve 22 is lowered to its normal position which is shown in Fig. 1. If any water splashes into the device, it is normally stopped by baffle wall 10.

In an extreme case, water may splash into pipe 11, through ports 14. In such case, the water will collect in a pool W above valve seat 33, so that the weight of such accumulated water will open valves 34 and 39, and excess water will pass out of extension pipe 37. For this purpose pipe 27 can be located directly adjacent stop 24.

In the preferred normal position of float-valve 22, it is only slightly spaced from the rim of casing 2. This normal spacing will permit air freely to enter the casing 2, through its open bottom.

If the bottom of casing 2 remains open because the float-valve 22 is below its closing position, air can freely pass out of the apparatus when the diver exhales, so that it is not necessary, in such case, to open the valves 17 by excess internal pressure. In stormy weather, the float-valve 22 may close the bottom of casing 2 during substantial intervals. There is enough air in the casings 1 and 2 to supply the diver for a substantial period of time, even if the float-valve 22 temporarily closes casing 2.

In the second embodiment of Figs. 4, 5, 7, 8-14, the breathing device is applied to a helmet mask which has a water-proof wall 46, which may also be impermeable to poison gases. A tight closure for said helmet mask is provided by neckband belt 47, which encloses the flexible material of said helmet mask at the neck thereof.

Air-inlet pipe 48, which corresponds to pipe 11

of the first embodiment, is fixed to the hollow leg 49 of a coupling which is shown in Fig. 14. Said leg 49 has flanges 50a, between which wall 46 is clamped. The other hollow leg 50 of said coupling is threaded into leg 49. Said leg 50 has a pipe 48a, in which the ends of auxiliary flexible rubber pipes 51 and 52 are located. In effect, the air-inlet pipe 48 extends through wall 46, because legs 49 and 50 are extensions of air-inlet pipe 48. Each said auxiliary pipe 51 and 52 has its lower end connected to the leg 53a of a coupling, whose other leg 53 extends through a bore of the wall 46, at a respective ear-portion of the helmet mask. Each said auxiliary pipe 51 and 52 extends downwardly from its connection with the air inlet pipe. In effect, the lower end of each auxiliary pipe, because of each coupling 53a—53 is an extension of the respective auxiliary pipe. Flexible branch pipes 57 and 58 are respectively connected to auxiliary pipes 51 and 52. The respective open or free ends of said branch pipes 57 and 58 are held above the respective windows 59 of the helmet mask. As shown in Fig. 5, float valve 60 is fixed to a collar which is slidable on pipe 48. A stop 61 is fixed to pipe 48, thus limiting the downward sliding movement of the float valve 60. When the wearer of the helmet mask is floating in water, said float valve 60 is above the level of the water. The upper end of pipe 48 has spaced arms 64, to which the top of casing 62 is fixed. A top inner casing 68 is fixed to the top of casing 62. Said casing 68 has ports which are normally closed by valves 70, which are fixed to resilient biasing arms 69, which correspond to arms 18 and 40. Another float-valve 86 is slidably mounted on pipe 48. Said float-valve 86 has a stop 86a which is fixed to pipe 48. Perforated wall 63 is fixed to casing 62. The inner bottom casing 65 has a bottom annular flange which is fixed to flange 66 of casing 62. Casing 65 has ports 67. Casing 62 has valves 72 which are biased to close the ports 71 of casing 62 by resilient arms 72a.

As shown in Fig. 4 the mouth-portion of the helmet-mask has an opening in which tube 73 is located. When the helmet mask is used as a swimming mask, the insert pipe 79 is located in the position shown in Fig. 7. The insert pipe 79 has threading 78, by means of which said insert pipe 79 can be fixed to collar 75. Said collar 75 is hinged at 74 to tube 73, and it has a resilient latching tongue 76 which can releasably engage projection 77 of tube 73. Insert 79 has two valve seats, whose bores are normally closed by resilient valves 81 and 83, which are respectively fixed at 82 and 84 to said insert 79.

When the helmet mask is used as a swimming mask or as a nautical life-saving device, the wearer can float with the open bottom of casing 62 and float valve 60, held normally above the water. The body of the swimmer can be held vertical. When the swimmer inhales, air can pass into the open bottom of casing 62, through the bore of wall 63, through the space between pipe 48 and casing 68, through air-inlet pipe 48 and its extension members 49 and 50 into member 48a, and through auxiliary pipes 51 and 52 and through branch pipes 57 and 58, into the sealed interior of the helmet mask, into which no water can enter. No air can enter said helmet mask save through branch pipes 57 and 58. Since the fresh air flows over the windows 59, said windows 59 do not cloud.

No water can enter through members 53 and 53a, because they are respectively provided with

float-valves 55 and 56, which can close the bores 55a and 56a of the respective valve seats.

If any water tends to splash into casing 65, this is prevented or minimized by float-valve 60, which will rise on pipe 48 to close the open bottom ends of casings 62 and 65. The wall 63 also tends to prevent any water from splashing above the same. If any water splashes above wall 63, float valve 86 will rise on pipe 48 to close the casing 68 and the space between casing 68 and pipe 48. Hence I provide several means for preventing water from flowing into the helmet mask through pipe 48.

When the swimmer exhales, the valves 81 and 83 at the air-outlet part of the mask can flex outwardly, so that air can pass out of the helmet mask in the direction of the arrow of Fig. 7.

If any water enters the pipe 48, said water will flow through auxiliary pipes 51 and 52 to force the float-valves 55 and 56 away from their respective valve seats, so that the water will flow out of members 53. The branch pipes 57 and 58 have sufficient rigidity to have the normal shape shown in Fig. 11, so that each said branch pipe 57 and 58 always extends upwardly from its junction with the respective auxiliary pipe 51 and 52. Hence water cannot normally flow through said branch pipes 57 and 58 into the sealed interior of the helmet mask.

If any water enters the helmet mask, it can pass out through the outlet pipe 87, which is provided in an opening at the bottom of the wall 46. The bottom end or outlet of pipe 87 is normally closed by resilient valve 89, which is fixed by pin 90 to pipe 87. Pipe 87 also has a float-valve 88. When water accumulates in the interior of the helmet mask, said water will downwardly force valves 88 and 90, so that excess water can flow out of the helmet mask.

This helmet mask can be used as a gas mask by reversing the position of insert 79 from the position of Fig. 7 to the position of Fig. 6, and by connecting the mouth 80 of insert 79 to a pipe 85. Said pipe 85 is connected to a source of pure air or to a filter, which will remove the poison gas from the air.

The wearer will now inhale through insert 79, whose valves 81 and 83 will now flex inwardly during each inhalation. When the device is used as a gas mask, the pipe 48 and the parts fixed thereto are removed, and member 50 is sealed. When the wearer exhales, valve 89 will open outwardly.

The embodiment of Fig. 15 shows a partial mask 91 which covers the mouth and nose. Said partial mask 91 is held in position by belts 92 and 93. Belt 93 passes through rigid straps 95 which

are fixed to a pipe 94, which is coupled to pipe 48. The outlet pipe 87a corresponds to pipe 87 and outlet valve 89a corresponds to valve 89. The wearer exhales through pipe 96, which has a one-way valve 97, of the type of valve 89. The upper end of pipe 48 is connected to the apparatus which is shown in Figs. 4 and 5.

The preferred embodiment is the one which includes the use of a helmet. In using this device, 10 the buoyancy of the body of the wearer, plus the buoyancy of a float (whose use is optional), is sufficient normally to keep the air inlet of the helmet above the surface of the water. However, many of the features of the helmet can be used 15 in divers' helmets.

The helmet which is shown in Fig. 4 may have a rigid wall, save at its neck portion. If any water splashes into the space between pipe 11 and casing 12, said water can open valves 44 and pass 20 out through the respective ports. Likewise, water pressure can open the valves 17, in order to discharge water from casing 1.

The insert 79 has a mouth 80.

I claim:

1. A swimming helmet which has an air-outlet port, an air-inlet pipe which extends through the wall of said helmet, said air-outlet port having one-way valve means which permit the flow of air only outwardly through said air-outlet port, said 25 valve means being biased to closing position, said air-inlet pipe having an auxiliary pipe which is located in said helmet, said auxiliary pipe extending downwardly from its connection with said air-inlet pipe, the lower end of said auxiliary 30 pipe extending through a respective bore of said wall, said auxiliary pipe being provided at said lower end thereof with float valve-means which are biased by their buoyancy normally to close said lower end of said auxiliary pipe, a branch 35 pipe located in said helmet, one end of said branch pipe being connected to said auxiliary pipe intermediate the ends of said auxiliary pipe, said branch pipe extending upwardly from its connection with said auxiliary pipe, so that if 40 water enters said auxiliary pipe, said water will flow to said float valve means and open said float 45 valve means to escape from said auxiliary pipe, without flowing through said branch pipe.

2. A swimming helmet according to claim 1, in 50 which said helmet has a window, said branch pipe having a depending branch which has a free end, said free end being located adjacent said window, so that the air which enters the interior of said helmet through said free end sweeps across 55 said window.

SATURNINO TOFÉ BONILLA.
